UNITED STATES PATENT OFFICE.

WILLIAM S. HUTCHINSON, OF BETHLEHEM, PENNSYLVANIA.

ROOF CONSTRUCTION.

1,413,584.

Specification of Letters Patent. Patented Apr. 25, 1922.

Application filed May 15, 1919. Serial No. 297,212.

To all whom it may concern:

Be it known that I, WILLIAM S. HUTCHINSON, a citizen of the United States, and a resident of Bethlehem, in the county of 5 Northampton and State of Pennsylvania, have made a new and useful Invention in Roof Construction, of which the following is a specification.

My invention relates to building construction and in particular to the manner of supporting saw-tooth roofs by means of structural trusses.

In constructing factories and other similar types of buildings, it is customary to erect 15 the side walls to the minimum height necessary to provide sufficient working space and to erect thereon a roof consisting of alternate sloping panels of wood and glass facing respectively in diverging directions so 20 that a section through the roof presents the appearance which suggests its descriptive name, "saw-tooth." If the building walls are spaced a great distance apart, it is necessary to support the roof between the walls 25 by roof trusses and the bottom of such trusses must be high enough to afford room for ventilating, shafting, etc. These trusses will vary in depth in different buildings to afford sufficient strength. It is customary 30 to superimpose the saw-tooth roof on top of these trusses. This construction increases the building height to an amount correspond- 35 ing to the depth of the trusses and the object of my invention is to eliminate this in- crease in height as well as to eliminate sub- stantial amounts in the costs of material and labor as will be described below.

My invention is illustrated in the accompanying drawings forming part of this specification in which Figure 1 is a section through the upper walls and the roof of a building and is taken on a line parallel to the ridges and valleys of the roof such as line 1-1 of Fig. 2. Fig. 2 is a section on line 2-2 of 45 Fig. 1 showing a complete roof section.

Columns 1 or end walls 2, or both, support the roof trusses 3 which are composed of top chords 4, bottom chords 5 and transverse members hereinafter mentioned. Trusses 3 50 carry the roof purlins 6, 7 and 8 and are stiffened and braced laterally by these purlins and horizontal struts 9. The side walls 10 of the building may either extend to a horizontal level at the top of trusses 3 or may 55 follow the roof outline as I have indicated in Fig. 2. In either case, the roof, instead

of starting at the top of truss 3 and extending upwardly, is located substantially entirely between the horizontal planes of the top and bottom chords 4 and 5 of the truss. 60

Each truss includes the usual web members which are secured to its top and bottom chords. As shown in Figure 1, the truss is provided with vertical members 13, (one being shown), diagonals 11 and 11^a and 65 short braces 14, 15 and 16 between the diagonal 11 and the bottom chord. The diagonals 11 and 11^a aid in supporting the roof sections and as shown, the roof supporting purlin 7 is mounted on the diagonal 11. 70 With this arrangement each relatively sloping section of the roof structure is partially supported on a web member of each truss but the truss is independent of the roof section and merely forms a support therefor. 75 As shown, the short braces 14, 15 and 16 indirectly assist in supporting the roof section 12 and serve as intermediate braces in the roof truss. It will, of course, be understood that each roof truss may be provided with 80 two or more vertical members 13 and cooperating diagonal members such as are illustrated and that the roof supporting purlins 6, 7, and 8 together with the horizontal strut 9 strengthen the roof trusses by tying them 85 together and thereby bracing each truss laterally and holding the several trusses in parallelism.

The purlins 7 supporting the roof sheathing or sections 12 and the roof sash sections 90 17 are shown supported by transverse members mounted on the diagonals 11^a.

It is evident that if the above construction is used in place of the usual type, wherein the roof is superimposed above the roof trusses, there is a reduction in the cubical contents of the building equivalent to the area of the building multiplied by the depth of truss 3. This decrease in the space required to be heated results in large economy 95 in heating equipment and in the operation and maintenance thereof. There is a substantial decrease in the height of wall erected equivalent to the depth of truss 3. There is also a substantial saving of steel due to the combining of the functions of the truss diagonals and uprights with the roof rafters, posts and braces; thus eliminating one of these sets of parts; and this is attended by a complementary saving of labor in fabricating and assembling. 105

All of above mentioned advantages are

secured without sacrificing a foot of head room as, in any construction, the working space is limited by the lower chord of truss 3 which is just as far from the floor of the 5 building with my construction as it would be if the roof were superimposed above the truss in the usual manner.

I claim:—

1. In a building structure two roof trusses 10 spaced horizontally and each comprising a top chord, a bottom chord spaced therefrom and web members between said chords, in combination with roof supporting members extending between the trusses and secured to 15 chord and web members thereof, and independently formed relatively inclined roof sections mounted on said roof supporting members and located substantially wholly between the two planes defined by the top 20 and bottom chords of said trusses.
2. In a building structure, two roof trusses 25 spaced horizontally and located in substantial parallel relation, each comprising a top chord, a bottom chord spaced therefrom and extending substantially parallel thereto, and web members secured to and extending between the top and bottom chords, in combination with roof supporting members extending between said trusses and secured to 30 chord and web members thereof, and a saw-tooth roof structure comprising relatively inclined roof sections formed independently of said trusses, located substantially entirely between the horizontal planes defined by 35 top and bottom chords of said trusses and supported by said roof supporting members.
3. In a building structure, two roof trusses 40 spaced horizontally and each comprising a top chord, a bottom chord and intermediate inclined web members secured to said chords, in combination with transverse roof-supporting tie members secured to chord and web members of both trusses, and relatively inclined roof sections mounted on said roof-supporting members and located substantially entirely between the upper and lower 45 planes defined by top and bottom chords of the two trusses and conforming in inclination to the inclination of supporting web members. 50

4. In a building structure, two horizontally spaced roof trusses, each comprising a top chord, a bottom chord spaced therefrom and vertical and diagonal web members extending between and secured to said top and bottom chords, in combination with load supporting members extending between said trusses and supported by the chords and web members thereof, and a saw-tooth roof structure comprising relatively inclined sections 60 formed independently of the roof trusses and supported on said load supporting members and located between said trusses and substantially entirely between the planes defined by the top and bottom chords thereof. 65

5. In a building structure, two horizontally spaced roof trusses, each comprising a top chord, a bottom chord spaced therefrom and vertical and diagonal web members extending between and secured to said top and 70 bottom chords, in combination with load supporting members extending between said trusses and supported by the chords and web members thereof, and a saw-tooth roof structure comprising relatively inclined sections 75 formed independently of the roof trusses and supported on said load supporting members and located between said trusses and substantially entirely between the planes defined by the top and bottom chords thereof. 80

6. In a building structure, two roof-trusses, spaced apart and located in substantially parallel relation and each comprising a top chord, a bottom chord spaced therefrom and vertical and diagonal web-members extending between and secured to said top and bottom chords, roof-supporting purlins extending between said trusses and secured to the top chords, web-members, and bottom chords thereof, in combination with oppositely-sloping independently-formed roof-sections supported on said purlins and located between said trusses and substantially entirely between the planes defined by the top chords and bottom chords respectively of 90 said trusses. 95

In testimony whereof, I have hereunto subscribed my hand this 6th day of May, 1919.

WILLIAM S. HUTCHINSON.
